DOOR LATCH

Kermit H. Burgin, Zionsville, Ind.

Application May 27, 1938, Serial No. 210,300

4 Claims. (Cl. 292—332)

This invention relates to door latches and the like and has for a primary object the provision of a self-energizing structure which will cause the door to become more securely latched and resistant to opening under vibration or pressure against the door toward a closed position.

A further important advantage of the invention lies in its inherent self-closing action after the latch member is carried past an initial striking position on the keeper, and at the same time in the further action of providing an initial kicking open of the door as the latch member is carried toward the disengaging position.

These and other objects and advantages of the invention will become apparent to those versed in the art in the following description of the invention as illustrated in one particular form in the accompanying drawings, in which

Fig. 1 is a fragmentary transverse section through a door and jamb showing the structure in top plan view embodying the invention and in that position where the latch member has been brought into initial contact with the keeper;

Fig. 2, a similar view in section but showing the latch mechanism operated to the closed door position;

Fig. 3, a vertical section on the line 3—3 in Fig. 2;

Fig. 4, a detail in elevation and partial section; and

Fig. 5, a transverse section on the line 5—5 in Fig. 4.

Like characters of reference indicate like parts throughout the several views in the drawings.

In the particular embodiment of the invention as herein shown and described, a latch member 10 is carried by a vertically disposed pin 11 which in turn is carried by a suitable bracket herein shown as the top and bottom walls of a housing 12, whereby the latch member 10 may be free to rock about the axis of the pin 11 in horizontal travel. This latch member 10 may assume a wide range of forms, the essential feature being that it be provided with an initial striking arm or tooth 13 to be in the path of a keeper 14, and further that this member 10 also have a follower arm or tooth 15 to rock around behind a projection 16 on the keeper.

It is preferable that the axis of rotation as determined by the pin 11 be positioned as near as possible to the outer ends of these members 13 and 15. To the inner end of the latch member 10 is rockably attached a pin or rod 17 by any suitable means such as the pin 18. This rod 17 extends from the latch member 10 to have a rear

portion slidingly guided through a suitable bracket such as the rear wall 19 of the housing 12. A compression spring 20 encircles the rod 17 and bears compressibly by its ends between the wall 19 and the end of the latch member 10. Thus, in order to rock the member 10 from one position to the other as, for example, from the position indicated in Fig. 1 to the position indicated in Fig. 2, the spring 20 must be compressed as the member 10 rocks, Fig. 4, to carry the rod 17 from one inclined position to another as the pivot pin 18 travels across the line between the axis of the pin 11 and the passage of the rear end of the rod 17 through the wall 19. Thus it is to be seen that the spring 20 will tend to retain the latch 10 toward either end of travel as indicated.

Referring to Figs. 1—4, as the door is brought to the closed position, the outer tooth member 13 will initially strike the keeper 14 against the outer projection 21 and then as the door is pushed on toward a closed position, the latch member 10 will be rocked in a counter-clockwise direction initially against the pressure of the spring 20 and then with the aid of the spring 20 until the member 10 is brought into the position as indicated in Figs. 2 and 4. In this closed position, it is to be noted that the spring 20 is then maintaining the tooth 15 in compressive contact with the inner side of the keeper projection 16, thereby tending to urge the door in further travel toward the closed position. It is contemplated that the door and jamb would be provided with the usual intervening yielding stops (not shown) against which stops the door would be yieldingly urged by the spring 20 through the latch member 10 and its keeper 14.

At the same time reverse travel of the door to carry the member to the position indicated in Fig. 1 permits the spring 20 to rock the member 10 against the outer face of the keeper tooth 21 and thereby tends to push the door outwardly away from the jamb. This degree of pressure to be applied in either case by the spring 20 may, of course, be varied to meet the action desired and also to be in accordance with the weights of doors encountered.

Since the spring 20 will normally exert considerable pressure tending to rock the member 10 against the inner face of the tooth 16 when the door is in the closed position, it is preferable that some mechanism operated by a door handle be provided in order to overcome this pressure of the spring 20 initially so as to permit ease of operation in opening the door. In the form herein shown, a handle 22 is mounted on a shaft 23, Fig. 55

3, rockably entering the housing 12 from the outside of the door so that the handle 22 may be turned in an up and down manner as is now customary on doors such as employed on automobiles and the like.

5 On the inner end of the handle shaft 23 is secured an arm 24 turned upwardly to extend through and be rocked in a fore and aft direction through a slot 25 in the top of the housing 10 12. A bell crank 26 is rockably mounted on the housing 12 by any suitable means, such as the vertically extending pin 27, to have one arm extend from the pivot part to engage with the pin 18 which extends upwardly through the arcuate 15 slot 28. In the form herein shown, this engagement is effected by having the pin 18 enter a slot 29 in the lever arm. The other arm of the lever 26 is carried from the pivot part of the lever to be in the path of the handle arm 24, herein shown 20 as interconnecting with the arm 24 by having the arm 24 extend upwardly through a slot 30. A spring 31 is provided to maintain the handle 22 in a normal inoperative position, this spring being interconnected with a pin 32 fixed to the 25 housing 12 and the upper end of the arm 24.

In the structure thus far described, pushing 30 downwardly on the handle 22 will cause the arm 24 to reach the end of the slot 30 so as to rock the lever 26 about its pivot 27 and thereby push 35 the pin 18 to that end of its slot 28 nearest the outer side of the door. This would be the action which would take place in going from the position of the members indicated in Fig. 2 to those positions indicated in Fig. 1, the positions 35 indicated in Fig. 1 being those following an initial action of the spring 28 as the handle 22 is released intending to open the door.

In order to prevent accidental opening of the door from the inside such as by pushing there- 40 against as might be the case when the mechanism is employed in automobile doors, a safety latch is employed which consists of a second bell crank lever 33 having its central portion mounted pivotally on the housing 12 by the pin 34 to 45 have an arm extending across back of the pin 18 to carry an abutment 35 thereon which may drop into the path of the pin 18 across the slot 28, as indicated in Fig. 2, when the latch member 10 is in its latched position. This member of 50 the bell crank 33 is normally urged into the path of the pin 18, as indicated, by means of a spring 36 secured between the pin 27 under the upper bell crank 26 and the outer end of the arm 37 which is a part of the bell crank 33 extending 55 from its pivot pin 34. The bell crank 33 is limited in its travel as induced by the spring 36 by reason of the arm 37 being carried along the side of the handle arm 24 adjacent the outer side of the door.

60 This arm 37 is further provided with a cam 38 in the path of the arm 24 and is so positioned that the arm 37 may be normally swung against the arm 24 by the spring 36 to allow the abutment 35 to be in the path of the pin 18 when 65 the door handle 22 is in its normal inoperative position, that position being the horizontal one in the present showing. Then upon initial downward rocking of the handle 22, the arm 24 will strike the cam 38 and thereby swing the bell crank 33 to carry the abutment 35 out of the path of the pin 18 and thus permit further travel of the arm 24 on to the end of the slot 30 so that the bell crank 26 may then be rocked to shift the latch member 10.

75 While I have herein shown and described my

invention in the one particular form, it is entirely obvious that many structural changes may be employed such as changing the direction of travel of the operating handle 22, the shape and arrangement of the contacting teeth on both the latching member and the keeper, and in specific details of the operating mechanism, all without departing from the spirit of the invention, and I, therefore, do not desire to be limited to that precise form beyond the limitations as may be imposed by the following claims.

I claim:

1. In a door latch having a keeper, a latch member rockable in directions of travel of the door in relation to the keeper, a pair of spaced apart abutments on the latch, an abutment presented by the keeper in the path of said latch abutments, a spring interposed between the latch member and a member relatively stationary in respect to the latch member, the spring connection with the latch being arranged to be shifted to either side of a line between the pivot axis of the latch member and a removed part of the spring, whereby the relative travel of the latch member across the keeper will cause an abutment of one to contact the abutment of the other and rock the latch member initially in opposition to and subsequently by the aid of said spring to carry a latch abutment back of a keeper abutment, a door handle, and means interposed between the handle and the latch member for rocking the latch member toward an unlatched position to shift the spring from a latched to an unlatched urging position, means to lock the latch member, and means to unlock the latch member by a movement of the handle before the latch member is moved by the handle.

2. In a door latch having a keeper, a latch member rockable in directions of travel of the door in relation to the keeper, a pair of spaced apart abutments on the latch, an abutment presented by the keeper in the path of said latch abutments, a spring interposed between the latch member and a member relatively stationary in respect to the latch member, a pin carried by the latch member and connecting the spring with the latch member, the spring connection with the latch being arranged to be shifted to either side of a line between the pivot axis of the latch member and a removed part of the spring, whereby the relative travel of the latch member across the keeper will cause an abutment of one to contact the abutment of the other and rock the latch member initially in opposition to and subsequently by the aid of said spring to carry a latch abutment back of a keeper abutment, a shiftable door handle, means interposed between the handle and the latch member for rocking the latch member away from its latched position in opposition to said spring, a safety abutment automatically shifting into the path of the pin and preventing the latch member from moving from its latching position comprising a bell crank lever having a shoulder on one leg normally resisting the movement of the pin, and means operated by the handle for initially shifting the safety abutment out of the path of the pin by moving the opposite leg of the bell crank lever to permit travel of the latch member thereafter by continued movement of the handle.

3. In a door latch having a keeper, a latch member rockable in directions of travel of the door in relation to the keeper, a pair of spaced apart abutments on the latch, an abutment presented by the keeper in the path of said latch

- 5 abutments, a spring interposed between the latch member and a member relatively stationary in respect to the latch member, the spring connection with the latch being arranged to be shifted to either side of a line between the pivot axis of the latch member and a removed part of the spring, whereby the relative travel of the latch member across the keeper will cause an abutment of one to contact the abutment of the other and rock the latch member initially in opposition to and subsequently by the aid of said spring to carry a latch abutment back of a keeper abutment, a door handle, a bell crank lever interengaging with the latch member, an arm of the lever having a longitudinal slot and means interconnecting the door handle with said lever through the slot whereby the latch member may be shifted directly by the handle after travel to the end of the slot.
- 10 4. In a door latch having a keeper, a latch member rockable in directions of travel of the door in relation to the keeper, a pair of spaced apart abutments on the latch, an abutment presented by the keeper in the path of said latch
- 15 abutments, a spring interposed between the latch member and a member relatively stationary in respect to the latch member, the spring connection with the latch being arranged to be shifted to either side of a line between the pivot axis of the latch member and a removed part of the spring, whereby the relative travel of the latch member across the keeper will cause an abutment of one to contact the abutment of the other and rock the latch member initially in opposition to and subsequently by the aid of said spring to carry a latch abutment back of a keeper abutment, a door handle, a lever interengaging with the latch member, and means interconnecting the door handle with said lever whereby the latch member may be shifted directly by the handle, an abutment on a bell crank lever normally urged into the path of travel of a member carried by the latch member, and cam means on the other arm of the bell crank lever from the abutment 20 operated by initial travel of the door handle shifting said abutment out of said path.

KERMIT H. BURGIN.
